UNITED STATES PATENT OFFICE.

JAMES B. DARROW, OF HINCKLEY, NEW YORK, ASSIGNOR OF ONE-HALF TO JOHN CAMERON, OF HINCKLEY, NEW YORK.

AUTOMATIC TRAIN-CONTROLLER.

1,211,099.

Specification of Letters Patent.

Patented Jan. 2, 1917.

Application filed July 23, 1915, Serial No. 41,589. Renewed September 25, 1916. Serial No. 122,130.

To all whom it may concern:

Be it known that I, JAMES B. DARROW, a citizen of the United States, residing at Hinckley, in the county of Oneida, State of New York, have invented certain new and useful Improvements in Automatic Train-Controllers; and I do hereby declare the following to be a full, clear, and exact description of the invention, such as will enable others skilled in the art to which it appertains to make and use the same.

The present invention is directed to improvements in automatic controls for railway trains, and has for its object to so construct a device of this character that should the engineer fail to observe a semaphore arm set for danger the throttle valve will be actuated to cut off the steam, thus bringing the train to a standstill.

20 A further object of the invention is to provide an automatic control of this type, provided with means for automatically applying the air brakes.

25 A still further object of the invention is to provide means whereby the engineer will be notified by a visual and audible signal that he has run past a signal set for danger.

With these and other objects in view, this invention resides in the novel features of 30 construction, formation, combination and arrangement of parts to be hereinafter more fully described, claimed and illustrated in the accompanying drawing, in which:—

Figure 1 is a fragmentary side elevation 35 of a locomotive equipped with the device. Fig. 2 is a vertical central sectional view through the steam dome of the locomotive, showing the throttle valve in its open position. Fig. 3 is a similar view, showing the 40 throttle valve closed. Fig. 4 is a sectional view on line 4—4 of Fig. 2. Fig. 5 is a detail perspective view of the circuit controlling lever. Fig. 6 is a sectional view on line 6—6 of Fig. 4. Fig. 7 is a similar view on 45 line 7—7 of Fig. 1. Fig. 8 is a similar view on line 8—8 of Fig. 1.

Referring to the drawing 1 indicates a locomotive of the usual construction. Mounted in the steam dome 2 is the usual casing 3, having the upper and lower seats 4 and 5, respectively. Coacting with the seats are valves 6 and 7, said valves being connected by a sleeve 8 which is slidably engaged with the stem 9. The stem 9 is connected in the 50 usual manner to the throttle lever 10.

The stem 9 is provided near its upper end with an annular groove 11 which is adapted to be engaged by the inner ends of the latches 12, said latches being slidably in casings 13 which are suitably connected to the upper surface of the valve 6. The latches 12 are urged inwardly by coil springs 14, which are mounted in the casings and have their rear ends engaged with the outer ends of the casing and their inner ends with the outer ends of the latches, said latches having their inner ends beveled, as at 15, the purpose of which will appear later.

The steam dome is provided with a stuffing box 16 in which slides a rod 17, the lower end of which is provided with a hollow head 18 having its lower edge beveled, as at 19, said beveled edge being adapted to coact with the beveled ends of the latches 12 for a purpose to be hereinafter described. 75

A bracket 20 is mounted upon the dome 2 and pivotally supports the lever 21, said lever having its forward end pivotally connected to the lower end of the link 22, the upper end of which is similarly connected 80 to the arm 23 which has its lower end pivotally connected to the locomotive boiler. The upper end of the arm 23 terminates in a vertical extension 24 which is pivotally engaged by one end of the curved arm 25, 85 said arm being held in its normal position by a spring latch 26 which is operable by a cord 27 which extends into the locomotive cab 28. The arm 23 is pivotally connected to the rod 17 by a link 29, whereby when the arm moves upwardly or downwardly the head 18 will also move upwardly or downwardly. 90

Mounted in the cab 28 are spaced guides 30 between which swings a lever 31 which 95 is provided with a spring catch 32 adapted to engage the notch 33 formed upon one of the guides, thereby holding the lever in a position so that the contact 34 carried thereby will engage the contact 35 carried by the 100 guides 30, thereby closing the circuit through the wires 36, thus sounding the bell 37 and lighting the lamps 38, which are arranged in the circuit. This lever has its lower end attached to a cord 39 which 105 connects said lever to the lever 21. Thus it will be seen that when the lever 21 rocks in one direction that the cord 39 will swing the lever 31 rearwardly, thereby causing the catch 32 to automatically operate to lock 110

the lever until the same is manually released. Also mounted near the dome 2 is a valve 40 which is operatively connected to the arm 23 by a link 41, whereby when 5 the arm is rocked downwardly the valve will be actuated to apply the air brakes.

From the foregoing description it will be seen that should the locomotive be in motion the valves 6 and 7 will be naturally 10 unseated, but should the arm 25 contact with a semaphore arm the arm 23 will swing downwardly thus moving the rod 17 downwardly until the head 18 thereof has moved sufficiently to cause the beveled edge 15 thereof to engage the beveled edges of the latches 12, whereupon the valves will seat, thus shutting off the supply of steam to the cylinders. Simultaneous with the operation of the head 18, valve 40 will be 20 actuated, thus applying the brakes. It is obvious that when the arm 23 swings downwardly that the lever 21 will be rocked, thus swinging the lever 31 until the latch 32 is in its locked position, and at which 25 time the engagement of the contacts 34 and 35 will close the circuit through the wires 36, thus sounding the bell and lighting the lamps 38 so as to immediately call the engineer's attention to the fact that the engine is being brought to a stop due to negligence.

It will be noted that the operation of the throttle valve is in no way affected by the addition of the latches 12, and that the engineer can control the same in the usual manner.

What is claimed is:—

1. In an automatic train control, a valve stem, a throttle valve normally locked to 40 the stem for movement therewith to and from its seat, and means automatically operable to release and actuate the valve independently of the stem to seat the same.

2. In an automatic control for locomotives, the combination of a valve stem, a 45 throttle valve slideable thereon to and from its seat, an arm supported by the locomo-

tive, latches carried by the throttle valve to normally lock same to stem, a head operable in the steam dome of the locomotive, 50 and means connecting the arm and head to actuate the latches upon movement of the arm downwardly, whereby said latches are actuated to permit the valve to slide on the stem to its seat, as and for the purpose set forth.

3. In an automatic control for locomotives, the combination with the throttle valve thereof, the stem of which is slidably connected to the valve, said stem having an 60 annular groove formed therein, spring actuated latches carried by the valve for engaging the groove, an arm supported by the locomotive, a head, and means connecting the head and arm, whereby movement 65 of the latter will cause the head to engage the latches to force them from engagement with the groove, as and for the purpose set forth.

4. In an automatic train control, a valve 70 stem, a throttle valve slideable on the stem, spring pressed latches carried by the valve, said stem having an annular groove for engagement by the latches, a head, an arm, means connecting the head and arm to cause 75 the former to disengage the latches from the groove when the latter is moved downwardly, thereby closing the valve, and means operable by the arm for indicating that the valve has been closed. 80

5. In an automatic train control, a valve stem, a throttle valve slideable on the stem, means normally locking the valve to said stem for movement therewith to and from its seat, and means automatically operable 85 to release said locking means and subsequently slide the valve on said stem to its seat.

In testimony whereof, I affix my signature, in the presence of two witnesses.

JAMES B. DARROW.
